UNITED STATES PATENT OFFICE.

DANIEL P. PEWTHERS, OF PORTSMOUTH, OHIO, ASSIGNOR OF ONE-HALF TO
SMITH H. MONTGOMERY, OF SAME PLACE.

SPOOL-HOLDER.

SPECIFICATION forming part of Letters Patent No. 567,996, dated September 22, 1896.

Application filed February 21, 1896. Serial No. 580,275. (No model.)

To all whom it may concern:

Be it known that I, DANIEL P. PEWTHERS, of Portsmouth, in the county of Scioto and State of Ohio, have invented certain new and useful Improvements in Spool-Holders; and I do hereby declare the following to be a full, clear, and exact description of the invention, such as will enable others skilled in the art to which it appertains to make and use the same.

10 My invention relates to an improvement in spool-holders, the object being to provide a simple, durable, and attractive device for holding thread, ribbon, braid, tape, and the like, either wound on spools or in balls, where-
15 by the material supported is prevented from being unwound or soiled when not in use.

A further object is to so arrange the parts that any amount of the material supported may be easily and quickly unwound and se-
20 vered, the cutting-point being sufficiently re-
moved from the unwinding-point as to allow a sufficient amount of material exposed and ready for grasping by the operator when ad-
ditional material is required.

25 With these ends in view my invention con-
sists in certain novel features of construction and combinations of parts, as will be herein-
after more fully described, and pointed out in the claims.

30 In the accompanying drawings, Figure 1 represents a view of my improvement in its operative position, and Fig. 2 is a similar view with the spool removed.

A represents a rectangular frame, prefer-
35 ably made up of a single piece of wire bent at the bottom to form spiral springs 1 1, the inner coils of which terminate in an upwardly-
extending spring-support or spool-holder 2, which latter is maintained in a position co-
40 incident with vertical sides 3 4 of said rec-
tangular frame by reason of its outwardly-
curved upper end 5 engaging top 6 of said rec-
tangular frame. This curved upper end 5 also acts as a stop and prevents lateral
45 movement of said spring-support beyond its normal position by striking against the upper end of the frame. Vertical side 3 is prefer-
ably composed of two members, between which the end of the material or thread supported
50 on spring-support or holder 2 is adapted to be held, while vertical side 4 is provided with a

cutting edge 7 for severing said thread or material in desired lengths.

In mounting or removing the spool 8 the support or holder 2 is pushed to one side 55 against the action of the spiral springs 1 1, after which said spring support or holder is released, whereupon it immediately assumes its normal or locked position by reason of the action of said spiral springs, which latter also 60 maintain said support or holder in the position above stated. The article carried by said support or holder 2 is prevented from turning when not in use by reason of its spring action against the spool or ball mounted there-
on. This spring action, however, is not suf-
ficient to retard the free movement of the
spool or ball when the thread or material sup-
ported thereon is being unwound. Before
20 removing any of the thread or material sup-
ported on holder 2 the end thereof is first
passed between the members constituting
side 3, after which any desired length may be
unwound and cut off. By severing the thread
or material after its passage between the
members constituting side 3, and at a point
70 directly opposite said side, the severed end
of the material supported is always accessi-
ble, and hence additional material or thread
can be obtained when desired without being
75 required to rethread said severed end.

From the foregoing it will be seen that my invention is extremely simple, easy of opera-
tion, and that when not in use the article sup-
ported is prevented from being wasted or 85
soiled.

Having fully described my invention, what I claim as new, and desire to secure by Letters Patent, is—

1. As an article of manufacture, a spool-
holder comprising a strip of metal or wire bent
to form sides and ends adapted to surround
the sides and ends of a spool, and a centrally-
located support or holder extending from one
end to the other, said holder or support hav-
ing a spring-hinged connection with one end
90 of the frame whereby to hold the free end of
the holder or support with yielding contact
against the opposite end of the frame, where-
by the spool may be removably held in place
95 in the frame, substantially as set forth.
2. As an article of manufacture, a spool-

holder composed of wire bent to form two sides and an end of a spool-holding frame, a spiral spring at one end and a central spool holder or support extending from the inner ends of the spring to the end bar against which the free end of the support or holder normally rests, the wire at one side folded to form two members between which to receive the thread and at the other side sharpened to

form a knife or cutting edge for cutting the thread.

In testimony whereof I have signed this specification in the presence of two subscribing witnesses.

DANIEL P. PEWTHERS.
